GEORGE J. LOWRES, OF NEWARK, NEW JERSEY.

EYEGLASS-MOUNTING.

1,115,700.

Specification of Letters Patent.

Patented Nov. 3, 1914.

Application filed July 19, 1913. Serial No. 780,011.

To all whom it may concern:

Be it known that I, GEORGE J. LOWRES, a citizen of the United States, residing at Newark, in the county of Essex and State of New Jersey, have invented certain new and useful Improvements in Eyeglass-Mountings; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in eye-glass mountings; and, the present invention has reference, more particularly, to a novel form and construction of mounting for use with the lenses of eyeglasses and spectacles, with a view of providing a mounting of the general character hereinafter more especially set forth, and which is readily secured to and removed from the lens without the employment of the usual fastening screw, the stud of the mounting being made in the form of a snap-catch which is readily sprung into place with the lens and is of such construction, that the parts are positively secured with relation to each other, but may be easily and quickly disconnected for separating the lens from the mounting.

The present invention, therefore, has for its principal object to provide a simply constructed eye-glass mounting having the characteristics hereinabove mentioned, the device being of such a construction so that it can be easily applied to lenses varying in thickness, without changing or disturbing the parts of the mounting when attaching it to the lens.

The invention has for its further object to provide a detachable stud for the lenses of eye-glasses and spectacles which can be readily fitted and secured in place at the edge of the lens without observing due care, and without the least danger of cracking or breaking the thin eye-glass lens, when making the attachment.

Other objects of this invention not at this time more particularly enumerated will be clearly understood from the following detailed description of the present invention.

With the various objects of the invention in view, the said invention consists, primarily, in the novel eye-glass mounting herein-

after set forth; and, the invention consists, furthermore, in the novel arrangements and combinations of the various devices and parts, as well as in the details of the construction of the said parts, all of which will be more fully described in the following specification, and then finally embodied in the clauses of the claim which are appended to and which form an essential part of this specification.

The invention is clearly illustrated in the accompanying drawings, in which:

Figure 1 is an enlarged fragmentary elevation of an eye-glass mounting and lens, illustrating one embodiment of the principles of the present invention; Fig. 2 is a central sectional representation of the parts illustrated in said Fig. 1, said section being taken on line 2-2 in Fig. 1, and showing the lens firmly mounted in position and supported by the stud; and Fig. 3 is a similar sectional representation, but illustrating the manner of attaching the stud upon the edge of the lens, or removing it therefrom. Fig. 4 is a side view of the detachable stud; and Fig. 5 is a view of the same, looking in the direction of the arrow α in said Fig. 4. Fig. 6 is a central sectional representation of an eye-glass mounting and a portion of a lens to which it is attached, of a slightly modified construction. Fig. 7 is a fragmentary elevation of an eye-glass mounting and lens, similar to Fig. 1, but showing still another modified construction embodying the principal features of the present invention; and Fig. 8 is a central sectional representation, similar to Fig. 2, of a portion of an eye-glass lens and a detachable mounting therefor of another modified construction. Fig. 9 is a perspective view of the stud employed in the form of mounting represented in said Fig. 8; and Fig. 10 is a perspective view of a hook-provided plate, also employed with the form of mounting illustrated in said Fig. 8.

Similar characters of reference are employed in all of the above described views, to indicate corresponding parts.

Referring now to the figures of the drawings, the reference-character 1 indicates the usual lens provided near its marginal edge-portion and upon the major axis of the lens with a screw-post receiving hole 2. Arranged and permanently fixed in this hole 2 is a screw-post 3, which is provided with an integral collar 4 forming a flange resting directly upon one of the surfaces, as 5, of

the lens. That portion of the screw-post 3 above said collar 4 is provided in its end with a groove or slit, as 6, for the reception of a screw-driver, and the opposite end-portion of said post 3 is screw-threaded, as at 7. This screw-threaded end-portion of the post 3 extends beyond the surface 8 of the lens 1, and is screwed into a screw-threaded hole 10 of a flat pivot-plate 9, said plate being thereby brought to bear positively upon the surface 8 of the lens, and the screw-post 3 on account of its collar 4 bearing directly upon the surface 5 of the lens, being positively and permanently secured in its operative relation to the lens. The said flat plate 9 has that portion located near the marginal edge-portion of the lens, made preferably angular, as at 11, and as shown in Figs. 2, 3 and 6, so as to extend 20 slightly away from the surface 8 of the lens. The said angular portion 11 is also provided with a suitably formed and suitably disposed hook-receiving perforation or hole 12, for the purpose to be presently more 25 fully described.

The reference-character 13, in Figs. 1 to 7 inclusive, indicates a stud with which are integrally connected the arc-shaped strap-members or elements 14 which are adapted 30 to be fitted upon and engage the adjacent edge of the lens. The stud is also further provided with the flanges 15 between which are arranged in the usual manner, the end- 35 portions of the nose-bridge 16 and the nose-guards 17, the said end-portions being suitably secured in position by means of a screw 18, or any other suitable fastening means. Extending from the lower edge-portion of the inner flat surface 19 of the stud 13, is 40 a suitably formed hook or lug, as 20, adapted to be inserted in the perforation or hole 12, hereinabove mentioned, and in alignment with said hook or lug 20 and extending from the upper edge-portion of said 45 flat surface 19 is a forwardly extending holding plate-like member or element, as 21, adapted to be arranged upon the flat surface 5 of the lens, and having its front end-portion preferably made much thinner than 50 the remaining portion of said plate-like member or element 21, said thin end-portion being pronged or bifurcated, as at 22, all being adapted to be arranged above the collar 4 of the screw-post 3 and embracing 55 that portion of the screw-post 3 above said collar 4, in the manner clearly represented in said Fig. 2 of the drawings. Suitably secured upon the upper surface of said plate-like member or element 21, by means 60 of a pin, rivet, or screw, as 23, or by means of any other suitable fastening means, is a holding catch 24, made in the form of a resilient spring-plate or finger, the free end-portion of which, when the hook or lug 20 65 has been inserted in the hole 12 and is piv-

otally moved in the direction of the arrow y , see Fig. 3, passes over the free end-portion of the screw-post 3, whereby a hole or perforation 25 in said resilient spring-plate or catch 24 is brought directly over the end 70 of the said screw-post, so that the said post enters the hole or perforation 25; and, with the said spring-plate or catch 24 snapping into holding engagement with the screw-post 3, it will be clearly evident that the 75 stud 13 and lens 1 will be securely connected with relation to each other, but may be just as readily separated when the spring-plate or catch 24 is raised into the dotted position indicated in said Fig. 2, and whereby the 80 stud can be swung into the position shown in Fig. 3 of the drawings, and readily separated from its holding engagement with the flat plate 9, so that the lens and stud will be brought into their separated relation, as will be clearly understood from an 85 inspection of said Fig. 3. To prevent the hook or lug 20 from entering too far into the hole or perforation 12, and thereby perhaps interfering with the pivotal movements of the parts, the hook-element or lug 20 is preferably made with a pair of offsets or shoulders, as 26, which coöperate with the part 11 of the flat plate 9, as will 90 be clearly evident.

The operation of the device or mechanism in bringing the stud and lens into their snapped engaged relation, and the manner of separating the stud and lens will be fully understood from the foregoing description, 100 and from an inspection of the several figures of the drawings, and need not, for that reason, be further described.

In lieu of the screw-post 3 and collar 4 formed integral therewith, a screw-post 27 105 may be employed, as indicated in Fig. 6 of the drawings, and a separate collar or washer 28 may be employed, the said collar or washer being suitably mounted upon said post 27. In all other respects, the construction of the 110 mounting is the same as that described in connection with Figs. 1 to 5 inclusive.

To avoid all possibility of the screw-post working loose and turning in the perforated portion of the lens 1, that portion of the 115 screw-post above the collar 4 or washer 28 may be serrated or fluted, as at 29, see Fig. 7, the resilient spring-plate or catch-element 30, which is secured to the stud in the manner hereinabove described, being provided 120 with a screw-post receiving hole which is correspondingly serrated or fluted, as at 30, adapted to be fitted over and register with the serrated or fluted part 29 of the screw-post, so as to lock with the same, and prevent 125 the said post from turning, as will be clearly understood from an inspection of said Fig. 7 of the drawings.

In the modified construction illustrated in Figs. 8, 9 and 10 of the drawings, I employ 130

a flat plate 31 having a screw-threaded hole 32 by means of which and the screw-post 3, the said plate is secured upon one of the faces of the lens. Upon its free end-portion, 5 at a point near the marginal edge of the lens, this plate is made with an outwardly extending hook-portion, as 33. The stud 34, in this case is provided at the lower edge of its flat surface-portion 34 with a projection, 10 as 35, said projection being provided with a suitably formed hook-receiving hole or perforation, as 36, by means of which the stud may be pivotally connected with the hook-portion 33 of the flat plate 31, so as to co- 15 operate therewith in the manner of the parts of the constructions illustrated in Figs. 1, 2, 3 and 6, and herein-above described.

The construction and operation of the remaining parts of the eye-glass mounting, as 20 will be seen from an inspection of said Fig. 8, is the same as that described in connection with the construction of eye-glass mountings illustrated in Figs. 1 to 7 inclusive, and need therefore not be further described at this 25 time.

I am fully aware that some changes may be made in the general arrangements and combinations of the various devices and parts, as well as in the details of the construction of the said parts, comprising my novel eye-glass mounting, without departing from the scope of the invention as described in the foregoing specification, and as set forth in the appended claims. Hence, I do 30 not limit my invention to the exact arrangements and combinations of the several devices and parts, as described in the said specification, nor do I confine myself to the exact details of the construction of the said 35 parts as illustrated in the accompanying drawings.

I claim:—

1. In eyeglasses, in combination with a lens, a pivot plate located upon one side of 45 the lens, a post extending through the lens for securing said plate in a fixed position relative to the lens, a stud provided with means for pivotally and detachably connecting the stud to said pivot plate, and means 50 connected with said stud adapted to be brought into holding engagement with the said post.

2. In eye glasses, in combination with a lens, a pivot plate located upon one side of 55 the lens, a post extending through the lens for securing said plate in a fixed position relative to the lens, a stud provided with means for pivotally and detachably connecting the stud to said pivot plate, and a resilient 60 spring catch connected with said stud and having a portion adapted to be sprung into holding engagement with a portion of said post.

3. In eye glasses, in combination with a 65 lens, a pivot plate located upon one side of

the lens, a post extending through the lens for securing said plate in a fixed position relative to the lens, a collar upon said post, said collar bearing upon the opposite side of the lens, a stud provided with means for pivotally and detachably connecting the stud to said pivot plate, and means connected with the said stud adapted to be brought into holding engagement with said post and its collar. 70

4. In eye glasses, in combination with a lens, a pivot plate located upon one side of the lens, a post extending through the lens for securing said plate in a fixed position relative to the lens, a collar upon said post, 80 said collar bearing upon the opposite side of the lens, a stud provided with means for pivotally and detachably connecting the stud to said pivot plate, and a resilient spring catch connected with said stud and having a portion adapted to be sprung with holding engagement with said post and its collar. 85

5. In eye-glasses, in combination with a lens, a pivot-plate located upon one side of the lens, a screw-post extending through the lens for securing said plate in a fixed position relative to the lens, a stud provided with means for pivotally and detachably connecting the stud to said pivot-plate, a holding plate connected with said stud, said 90 plate being adapted to be arranged upon the other side of the lens and having a bifurcated end adapted to embrace said screw-post, and means connected with said plate adapted to be brought into holding engagement with the said screw-post. 95

6. In eye-glasses, in combination with a lens, a pivot-plate located upon one side of the lens, a screw-post extending through the lens for securing said plate in a fixed 105 position relative to the lens, a stud provided with means for pivotally and detachably connecting the stud to said pivot-plate, a holding element connected with said stud, said element being adapted to be arranged upon the other side of the lens and having a bifurcated end adapted to embrace said screw-post, and a resilient spring-catch connected with said element and having a perforated portion adapted to be sprung into 110 holding engagement with a portion of said screw-post. 115

7. In eye-glasses, in combination with a lens, a pivot-plate located upon one side of the lens, a screw - post extending through 120 the lens for securing said plate in a fixed position relative to the lens, a collar upon said screw-post, said collar bearing upon the opposite side of the lens, a stud provided with means for pivotally and detachably connecting the stud to said pivot-plate, a holding plate connected with said stud, said plate being also adapted to be arranged upon said opposite side of the lens and having a bifurcated end adapted to embrace the collar. 125 130

of said screw-post, and means connected with said plate adapted to be brought into holding engagement with said screw-post and its collar.

5 8. In eye-glasses, in combination with a lens, a pivot-plate located upon one side of the lens, a screw-post extending through the lens for securing said plate in a fixed position relative to the lens, a collar upon said 10 screw-post, said collar bearing upon the opposite side of the lens, a stud provided with means for pivotally and detachably connecting the stud to said pivot-plate, a holding plate connected with said stud, said plate 15 being also adapted to be arranged upon said opposite side of the lens and having a bifurcated end adapted to embrace the collar of said screw-post, and a resilient spring- 20 catch connected with said plate and having a perforated portion adapted to be sprung with holding engagement with said screw- post and its collar.

9. In eye-glasses, in combination with a lens, a pivot-plate located upon one side of 25 the lens, said pivot-plate being provided with a hook-receiving perforation, a screw- post extending through the lens for securing said plate in a fixed position relative to the lens, a stud, a hook extending from said 30 stud, said hook being pivotally inserted in the perforation of said pivot-plate, and means connected with said stud adapted to be brought into holding engagement with the said screw-post.

35 10. In eye-glasses, in combination with a lens, a pivot-plate located upon one side of the lens, said pivot-plate being provided with a hook-receiving perforation, a screw- post extending through the lens for securing 40 said plate in a fixed position relative to the lens, a stud, a hook extending from said stud, said hook being pivotally inserted in the perforation of said pivot-plate, and a resilient spring-catch connected with said 45 stud and having a portion adapted to be sprung into holding engagement with a portion of said screw-post.

11. In eye-glasses, in combination with a lens, a pivot-plate located upon one side of 50 the lens, said pivot-plate being provided with a hook-receiving perforation, a screw- post extending through the lens for securing said plate in a fixed position relative to the lens, a collar upon said screw-post, said 55 collar bearing upon the opposite side of the lens, a stud, a hook extending from said stud, said hook being pivotally inserted in the perforation of said pivot-plate, and means connected with said stud adapted to be brought into holding engagement with 60 said screw-post and its collar.

12. In eye-glasses, in combination with a lens, a pivot-plate located upon one side of the lens, said pivot-plate being provided 65 with a hook-receiving perforation, a screw-

post extending through the lens for securing said plate in a fixed position relative to the lens, a collar upon said screw-post, said collar bearing upon the opposite side of the lens, a stud, a hook extending from said 70 stud, said hook being pivotally inserted in the perforation of said pivot-plate, and a resilient spring-catch connected with said stud and having a portion adapted to be sprung into holding engagement with said screw- 75 post and its collar.

13. In eye-glasses, in combination with a lens, a pivot-plate located upon one side of the lens, said pivot-plate being provided with a hook-receiving perforation, a screw- 80 post extending through the lens for securing said plate in a fixed position relative to the lens, a stud, a hook extending from said stud, said hook being pivotally inserted in the perforation in said pivot-plate, a holding plate connected with said stud, said plate 85 being adapted to be arranged upon the other side of the lens and having a bifurcated end adapted to embrace said screw- post, and means connected with said plate 90 adapted to be brought into holding engagement with the said screw-post.

14. In eye-glasses, in combination with a lens, a pivot-plate located upon one side of the lens, said pivot-plate being provided 95 with hook-receiving perforation, a screw- post extending through the lens for securing said plate in a fixed position relative to the lens, a stud, a hook extending from said stud, said hook being pivotally inserted in the perforation in said pivot-plate, a holding plate connected with said stud, said plate 100 being adapted to be arranged upon the other side of the lens and having a bifurcated end adapted to embrace said screw- post, and a resilient spring-catch connected with said plate and having a perforated portion adapted to be sprung into holding 105 engagement with a portion of said screw- post.

15. In eye-glasses, in combination with a lens, a pivot-plate located upon one side of the lens, said pivot-plate being provided with a hook-receiving porforation, a screw- 115 post extending through the lens for securing said plate in a fixed position relative to the lens, a collar upon said screw-post, said collar bearing upon the opposite side of the lens, a stud, a hook extending from said stud, said hook being pivotally inserted in the perforation in said pivot-plate, a holding plate connected with said stud, said plate 120 being also adapted to be arranged upon said opposite side of the lens and having a bifurcated end adapted to embrace the collar of said screw-post, and means connected with said plate adapted to be brought into holding engagement with said screw-post and its collar.

16. In eye-glasses, in combination with a 130

- lens, a pivot-plate located upon one side of the lens, said pivot-plate being provided with a hook-receiving perforation, a screw-post extending through the lens for securing said plate in a fixed position relative to the lens, a collar upon said screw-post, said collar bearing upon the opposite side of the lens, a stud, a hook extending from said stud, said hook being pivotally inserted in the perforation in said pivot-plate, a holding plate connected with said stud, said plate being also adapted to be arranged upon said opposite side of the lens and having a bifurcated end adapted to embrace the collar of said screw-post, and a resilient spring-catch connected with said plate and having a perforated portion adapted to be sprung into holding engagement with said screw-post and its collar.
17. In eye-glasses, in combination with a lens, a pivot-plate located upon one side of the lens, said pivot-plate having a perforated angular portion extending away from the side of the lens, a stud, and a hook extending from said stud into the perforation of said angular portion for pivot connection with said angular portion, a spring-catch connected with said stud, and means adapted to be engaged by said spring-catch for detachably connecting said stud to said pivot-plate.
18. In eye-glasses, in combination with a lens, a pivot-plate located upon one side of the lens, said pivot-plate having a perforated angular portion extending away from the side of the lens, a stud pivot-connection with said angular portion, a spring-catch connected with said stud, and a hook extending from said stud into the perforation of said angular portion for and a screw-post

extending through the lens and connected with said pivot-plate, said screw-post being adapted to be engaged by said spring-catch for detachably connecting said stud to said pivot-plate and said screw-post.

19. In eye-glasses, in combination with a lens, a pivot-plate located upon one side of the lens, said pivot-plate having an angular portion extending away from the side of the lens, said angular portion being provided with a hook-receiving perforation, a stud, and a hook extending from said stud, into the perforation of said angular portion for pivot-connection with said perforation, a spring-catch connected with said stud, and means adapted to be engaged by said spring-catch for detachably connecting said stud to said pivot-plate.

20. In eye-glasses, in combination with a lens, a pivot-plate located upon one side of the lens, said pivot-plate having an angular portion extending away from the side of the lens, said angular portion being provided with a hook-receiving perforation, a stud, and a hook extending from said stud into the perforation of said angular portion for pivot-connection with said perforation, a spring-catch connected with said stud, and a screw-post extending through the lens and connected with said pivot-plate, said screw-post being adapted to be engaged by said spring-catch for detachably connecting said stud to said pivot-plate and said screw-post.

In testimony, that I claim the invention set forth above I have hereunto set my hand this 18th day of July, 1913.

GEORGE J. LOWRES.
